UNITED STATES PATENT OFFICE.

NATHANIEL L. BRADLEY, OF WEST MERIDEN, CONNECTICUT, ASSIGNOR TO
BRADLEY & HUBBARD, OF SAME PLACE.

DESIGN FOR A LAMP-PEDESTAL.

Specification forming part of Design No. **7,162**, dated February 10, 1874; application filed November 22, 1873.
[Term of Patent 7 years.]

C.

To all whom it may concern:

Be it known that I, NATHANIEL L. BRADLEY, of West Meriden, in the county of New Haven and State of Connecticut, have invented a new Design for Lamp-Pedestal; and I do hereby declare the following, when taken in connection with the accompanying drawings and the letters of reference marked thereon, to be a full, clear, and exact description of the same, and which said drawings constitute part of this specification, and represent a perspective view.

This invention relates to a design for a base or pedestal upon which the bowl of the lamp rests as a support; and it consists in the peculiar configuration of the pedestal between the base proper and the bowl, it only being essential that the bowl and base be present as a part of the design, but their configuration may be varied.

Upon the base A the pedestal sits, and is in the shape of a vase. Starting from the flat surface of the pedestal, the foot of the vase runs up and inward, in a concave line, to the smallest diameter, at about one-fourth the height of the vase. From that point the body rises, gradually expanding in a curved line or bulging form to the top, where a band is

formed, from which, upon opposite sides, ears project, with a leaf extending up onto the neck, and in each of the ears a ring is set. From this band the neck is drawn inward, in an inverted ogee form, and upon the mouth the fount B is set.

The form of the base and fount is no part of this design, it only being essential that some form of base and fount be present.

I claim as my invention—

1. The design for lamp-pedestal, consisting of the vase resting upon a base, A, the foot drawing in toward the center in a concave form, the body rising therefrom, and gradually expanding in a convex form to a band; thence contracting, in an inverted ogee form, to the mouth, upon which rests the fount B, as shown and described.

2. The design for lamp-pedestal, consisting of a vase resting upon a base, A, and supporting the fount B, the said pedestal being provided with ears upon opposite sides, and a ring in each ear, as shown and described.

N. L. BRADLEY.
